UNITED STATES PATENT OFFICE

JOSEPH EVERETT LODGE, OF MAYWOOD, ILLINOIS, ASSIGNOR TO WESTERN ELECTRIC COMPANY, INCORPORATED, OF NEW YORK, N. Y., A CORPORATION OF NEW YORK

METHOD OF AND APPARATUS FOR HANDLING STRAND MATERIAL

Application filed April 6, 1929. Serial No. 353,041.

This invention relates to a method of and apparatus for handling strand material, and more particularly to a method of and an apparatus for handling a plurality of moving wires during a process of applying coating material thereon.

The invention is particularly applicable to the handling of moving wires which are in the process of being covered with rubber compound or other insulating substance and are also being vulcanized or otherwise treated in a closed chamber. In such process a plurality of wires are moved in parallel relation through an extrusion machine where an insulating covering is applied to them, and are then passed through an elongated chamber wherein they are subjected to the action of steam or other heating medium to effect a heat treatment of the covering. For example, two parallel wires may be simultaneously passed through the apparatus, the respective wires being drawn from separate supply reels, simultaneously passed through the extrusion machine where a covering of rubber or other insulating material is applied to them, and then passed in parallel relation through a closed steam chamber to effect vulcanization of the rubber, the steam chamber, at the point where the moving wires emerge being provided with a suitable seal to prevent leakage of the steam from the chamber.

Objects of this invention are to provide an improved method of and apparatus for expeditiously handling moving strands.

In accordance with the present invention, means are provided whereby when a reel becomes exhausted of wire the apparatus need not be stopped but the forward end of the wire from a succeeding reel may be fed into the extrusion machine and, during its passage through the steam chamber, attached to the other (continuous) wire by means of a clip or similar fastening member. The two wires are thereby bound together so that as the continuous wire is drawn forwardly it draws the wire of the new reel with it, and the forward end of the wire of the new reel is thus drawn through the steam chamber and seal by the continuous wire.

The invention will be more fully under-

stood from the following description taken in connection with the appended drawings, in which.

Fig. 1 is a diagrammatic elevation, partly in section, of a device embodying the invention and by means of which the invention may be practiced,

Fig. 2 is an enlarged sectional view, taken on the line 2—2 of Fig. 1, showing the mechanism for attaching clips to the wires,

Fig. 3 is a sectional view taken on the line 3—3 of Fig. 2,

Fig. 4 is an enlarged sectional view taken on the line 4—4 of Fig. 3, and

Fig. 5 is an enlarged sectional view taken on the line 5—5 of Fig. 3.

In the drawings, the reference numeral 9 designates the insulating head of an extrusion machine of any suitable construction adapted to simultaneously apply under pressure a covering of rubber compound or other material 10 to wires 11 and 12 which pass therethrough from supply reels 13, 14 and 15. The extrusion machine may be of any suitable type, such as that shown in the application of G. L. Cherry, Serial No. 353,042, filed April 6, 1929, and may be designed to apply a common covering to the two wires of the form illustrated in Fig. 5, or may apply separate coverings thereto, as desired.

The supply reels are so mounted with respect to the extrusion machine that when one reel becomes exhausted the wire from another reel may be threaded into the machine without removing the exhausted reel. From the extrusion machine, the newly coated wires are passed to a chamber 16, where steam or other heating medium is admitted thereto through an inlet 17, the heating medium being maintained under pressure in said chamber. From chamber 16 the coated and heat treated wires pass through a substantially steam-tight seal 18, and thence over a capstan 19 to a take-up reel 20. Capstan 19 is driven, by means not shown, at a predetermined speed which is coordinated with the extruding speed of the insulating head 9.

The seal 18 may be of any suitable construction, the one illustrated in the accompanying drawings comprising a threaded cap

21 which holds apertured disks 22, of rubber or other resilient material against the end of the steam chamber 16. A hollow cylindrical retaining member 23 holds the disks 5 22 in a yielding contact with the coated wires 11 and 12 moving therethrough to prevent leakage of the steam from the chamber. The retaining member 23 is held in position by a bell-crank lever 24 which is yieldingly 10 urged against the retaining member by means of a piston 63 mounted in a cylinder 64 and actuated by compressed air or other pressure medium admitted through duct 65, the piston being yieldingly urged upwardly by a 15 coiled spring 66.

A clip-securing mechanism 25 is mounted on the chamber 16 at a point between the insulating head 9 and the outlet end of the chamber, for a purpose to be more fully described hereinafter.

The clip-securing mechanism comprises a block 26 having a cylindrical recess 27 communicating with chamber 16 and forming a sliding fit for a plunger 28 having a tapered 25 flange 29 engaging a correspondingly tapered wall 30 of the recess in steam-tight engagement. At its other end the plunger is provided with a detachable head 31, and the plunger is normally held in retracted position 30 by the steam pressure acting on flange 29 and also by means of a coiled spring 32 interposed between the block 26 and the head 31. At its inner end the plunger 28 is provided with a bifurcated forming member 33 35 adapted to cooperate with a clip holder 35 disposed diametrically opposite thereto with respect to the chamber 16 and adapted to hold a clip 36. A removable plug 38 is seated in block 26 to permit the insertion of plunger 40 28 in the assembling of the apparatus.

Clip holder 35 is fixedly mounted in a cylindrical loading member 40 which is slidably mounted in a cylindrical recess 41 in block 26, the recess being closed at its lower 45 end by means of a plug 42. The loading member 40 is provided with a pair of oppositely disposed slots 44 adapted to receive corresponding flanges 45 formed on the wall of recess 41 to hold the loading member 40 and clip holder 35 in proper alignment.

Member 40 is provided at its upper portion with a sealing head 46 having beveled surfaces 47 to prevent leakage of steam, and is also provided with a crank 50 which is 55 threaded into a bracket 51 fixed to block 26. At its lower end, crank 50 is provided with an annular flange 54 rotatably mounted in the sealing head 46. Loading member 40 is also provided with a recess 55 adapted to 60 align with chamber 16 when the loading member is in its raised position, to provide for free passage of the wires during the reloading operation.

In operation, wires 11 and 12 are drawn 65 from the supply reels 14 and 15 through the

insulating head 9, which forms an insulating coating thereon. The wires are then drawn through the steam chamber 16 and seal 18 in parallel relation, passing over capstan 19 to the take-up reel 20, the distance between capstan 19 and reel 20 being sufficiently great to permit the covering to cool and harden. When the wire on a given reel 14 is exhausted, its rear end 56 will be drawn through the apparatus, and the extrusion machine will thereafter produce a tube or section of insulation 57 having no wire therein but usually having sufficient tensile strength to prevent its breaking before the forward end 58 of the wire on the next reel has advanced for some distance into the steam chamber 16. The operator may therefore pass the forward end 58 of the next reel 13 through the extrusion machine, whence it will be advanced into chamber 16 by the pressure of the covering material being extruded. When the forward end 58 has passed the clip-securing mechanism 25, the operator will secure the two wires 11 and 12 together by striking the head 31 with a mallet or other instrument. This results in the forming member 33 being forced against the clip holder 35 in such a manner as to cause the clip 36 to be bound around the wires in the manner illustrated in Fig. 4, the forward end 58 being thereby secured to the continuous wire 11, the interconnection being of sufficient strength to draw wire 12 through the seal by the tension exerted on wire 11 by capstan 19, and to permit the wires thereafter to be wound and otherwise handled in the usual manner. The clip also has the advantage of marking the point at which the connection has been made, thereby facilitating the later removal of the section 57 preparatory to splicing the two ends 56 and 58.

It will be evident that the operation of the clip-securing mechanism 25 does not necessitate arresting the movement of wires 11 and 12, as its action is almost instantaneous and its withdrawal very quickly effected by the steam pressure in chamber 16 as well as by the spring 32. The movement of the wires while the clip is being secured thereto results in the material 10 being stripped therefrom for a short distance, as indicated at 60, and compacted rearwardly of the clip, as indicated at 61, in Figs. 3 and 4. The clip having been applied to the wires, the loading member 40 may be withdrawn to the position indicated in dotted lines in Fig. 2 by rotating handle 50, thereby raising member 40 until recess 55 registers with chamber 16 and clip holder 35 is raised above the upper surface of block 26. In this position, a new clip may be inserted in holder 35 and the member 40 returned to its normal position. It should be noted that this reloading operation does not permit the escape of any substantial amount of steam from chamber 16.

While the invention has been described 150

- with particular reference to a pair of wires having a common covering, and to a steam vulcanizing process, it will be readily understood that both the apparatus and method, 5 with suitable modifications, may be applied in various other relations where it is desired to attach a plurality of moving strands together without interrupting their movement. The scope of the invention is therefore to be 10 limited only by the terms of the following claims:
- What is claimed is:
1. A method of handling strand material, comprising advancing a strand along a predetermined path, applying a covering to said strand and subjecting the covering to pressure treatment during such advancement, and attaching another strand to the first mentioned strand during the pressure treatment. 20
  2. A method of handling strand material, comprising advancing a plurality of strands in parallel relation along a predetermined path, heat treating the strands during such advancement, and securing some of said strands together during such heat treatment without arresting their movement. 25
  3. A method of handling strand material, comprising continuously advancing a plurality of strands in parallel relation along a predetermined path, applying a continuous covering to each of the strands at one point along said path, connecting the rear end of an exhausted strand to the forward 35 end of a succeeding strand by means of the covering material, and connecting the forward end of the succeeding strand to another of the covered strands.
  4. An apparatus for handling strand material, comprising means for moving a plurality of strands in parallel relation, a clip holding member positioned adjacent the path of the moving strands, and a clip forming member disposed oppositely to said clip holding member and adapted to be moved into engagement with the clip holding member. 45
  5. A device for handling strand material, comprising means for moving a plurality of strands in parallel relation, means for continuously heat-treating the strands during such movement, and means for securing some of said strands together during such heat treatment without arresting their movement. 55
  6. A device for handling strand material, comprising a container for a pressure medium, means for moving a plurality of strands through said container in parallel relation, and means for securing some of said strands together during their movement through said container. 60
  7. A device for handling coated wires, comprising a container for a gas under pressure, means for moving a plurality of coat- 65
- ed wires through said container, and means for securing some of said strands together during their movement through said container, said last mentioned means comprising a member projecting into the container and maintaining during its operation a seal against the escape of the gas. 70
8. In a device for handling strand material, a clip-securing mechanism having a passageway sealed against communication with the exterior of the mechanism, a clip holding member extending into said passageway and movable to a reloading position without establishing communication between the passageway and the exterior of the mechanism, and a clip forming member movable into cooperating relation to said clip holding member. 75
9. A device for securing together a plurality of strands during a treating operation, comprising a member having a passageway for the strands being treated, means for holding a securing member within said passageway, said means being movable to reloading position, and means cooperating with the first mentioned means for forming the securing member about the strands. 80
10. In an apparatus for handling strand material, a member having a passageway, means for advancing a plurality of strands through said passageway, and means for securing some of said strands together during their movement through the passageway, said last mentioned means comprising an element for holding a securing member within the passageway and means cooperating with the element for forming the securing member about the strands. 85
